UNITED STATES PATENT OFFICE.

MORRIS M. HIRSH, OF CHICAGO, ILLINOIS.

FREIGHT-CAR.

SPECIFICATION forming part of Letters Patent No. 340,579, dated April 27, 1886.

Application filed December 5, 1885. Serial No. 184,786. (No model.)

To all whom it may concern:

Be it known that I, MORRIS M. HIRSH, a citizen of the United States of America, residing at Chicago, in the county of Cook and State of Illinois, have invented certain new and useful Improvements in Railway Freight and Cattle Cars, of which the following is a specification, reference being had therein to the accompanying drawings.

10 This invention has for its object to construct a freight-car that can be converted from a box-car into a cattle-car, a coal or gravel car, or into a platform-car; and it consists of the novel devices and combinations of devices hereinafter described and specifically claimed.

15 In the accompanying drawings, Figure 1 represents a side elevation of the box-car; Fig. 2, a longitudinal vertical section through the center of the same; Fig. 3, a transverse vertical section through either end of such car; Fig. 4, a transverse vertical section through the center of the same; Fig. 5, a transverse vertical section through either end of the car as converted into a cattle-car; Fig. 6, a longitudinal vertical section through the center of such car as converted into a coal or gravel car; Fig. 7, a transverse vertical section through either end of the same as converted into a coal or gravel car, and Fig. 8 a transverse vertical section through either end of such car as converted into a platform-car.

20 Corresponding letters in the several figures of the drawings designate like parts.

A A' A² A³ denote the longitudinal floor-beams of the car-body, which are rigidly connected by end beams, B, and again the beams A and A', as well as the beams A² and A³, are transversely connected by a series of iron brace-bars, C.

25 Upon the beams A' and A² is rigidly secured a floor, D, which covers the space between such beams, and the spaces between A A' and A² A³ are covered by trap-doors E E', which by hinges are pivotally connected to the rigid floor D in a manner that such doors will form a continuation of such floor D.

30 F are the corner-posts, F' the door-posts, and F² intermediate posts tenoned into iron socket castings 2, that are rigidly secured upon the longitudinal beams A A³, and upon these posts F F' F² are secured by suitable castings,

3, the longitudinal beams G, framed together by end beams, 4, and by intermediate roof-plates, 5 and 6.

The roof for this car may be constructed in 55 any well-known manner.

The sides of this car between the corner-posts F and door-posts F' are closed, each such opening by a lower section, H, and an upper section, I, such sections forming a tight joint 60 at their meeting line. The section H is pivotally secured by hinges 7, to form a tight joint with the rabbeted inward upper edge of the floor-beams A or A³. Each section H is again divided longitudinally on its center line into 65 two sub-sections, a and b, that are pivotally secured together by strap-hinges 8 in a manner that the sub-section a can be folded upon the sub-section b, and that both sections thus folded can be turned down into the spaces between beams A and A' or A² and A³, to rest upon iron braces C, and when down to be covered and concealed by trap-doors E E'. The lower sub-section, b, is composed of longitudinal bars 9 9 and 10 and 10, that form rabbet-joints with each other. The bars 9 9 are secured to exterior upright bars, 11, and the intermediate bars, 10 10, which close the interstices between bars 9 9, are secured to interior upright bars, 12, each two such bars 11 70 and 12 being pivotally connected to one of the socket-castings 2 by a single hinge, l, that forms part of such socket-casting. With this construction, as will be seen, the bars 10 10, thus independently connected, can be turned down 75 into the spaces below the trap-doors E E', thereby providing openings between the bars 9 for ventilation and light, which will be desirable for transporting cattle or other livestock.

80 To posts F F' are secured plates that have pivotized latches 13 and 14, which latches pass through holes in sub-section a and in one of the bars 10, for rigidly fastening such parts on their upright position by keys 15, passed 85 through slots in the ends of such latches.

85 The sections I, forming the upper half of the side walls of the car-body, are composed each of a solid part, 16, and of bars 17 and 18, that form rabbeted joints with each other. The 90 solid part 16 and the bars 17 are rigidly secured to vertical bars 19, and the bars 18,

which close the interstices between bars 17, are secured to vertical bars 20, and each two such bars 19 and 20 are suspended by a single hinge, 21, formed to a casting, 22, secured to beam 5 G. With this arrangement each entire section I can be swung under the roof of the car, to be securely held on its upturned position by a turn-buckle or other fastening, 23, and when using such car for transporting cattle 10 the bars, 18, with their connecting-bars 20, can be swung up alone for ventilating and lighting purposes, and suspended to the roof of the car by hooks 24, engaging with eyes 25 of bars 20. The lower portion of the openings between door-posts F' are arranged to be closed 15 for grain, coal, or gravel transportation by doors J, each composed of two sections, c and d, connected by strap-hinges 26, and the section d again being pivotally coupled to post-sockets 2 by hinges 7, all in the same manner as described for section H, to fold such doors into the spaces between the floor-beams A A' or A' A³, where they are covered by trap-doors E E' when not required.

25 For closing the entire openings between posts F', I provide doors K, composed of slats 27, secured together by hinges 28. These slats move between channel-iron guide-grooves L, that are secured against the posts F, and are curved at 30 the top end of these posts, to be continued under the roof of the car on a horizontal line, where these channel-bars are secured to roof-plates 6, and for the two opposite doors, when both opened to clear each other, their guide-bars are placed on different elevations against 35 such roof-plates. The ends of the car I provide with doors M, constructed like doors K, and guided between channel-bars N, which are secured against the corner-posts, to be continued 40 on a horizontal line, where such channel-bars are fastened against the inward faces of longitudinal beams G, all as shown by Figs. 2, 4, and 7.

Instead of using doors M, I can also close 45 the ends of the cars by a frame-work, O, that divides such end area into panels which are closed by planking, and in one of the panels P I leave an opening to be closed by a sliding door or shutter, Q, suspended on rollers 29, 50 that ride upon a bar, 30, all as shown in Figs. 3, 5, and 8.

For better sustaining the sections H of the side walls of the car, particularly when such car is used for carrying coal or gravel, I provide 55 standards R, placed intermediate of posts F F' F², such standards R being pivotally secured by bolts S into exterior notches, T, of beams A A³ in a manner that when such car is converted into a platform-car such standards 60 can be turned into such notches T.

As shown by Figs. 1, 2, 3, and 4, the car is completely closed from all sides and ends, the same as a box-car; but when desired to be used as a car for transporting cattle or other live 65 stock the bars 10, with their hinge-bars 12, are turned under the trap doors E E', and the bars

18, with their hinge-bars 20, are suspended to hooks 24, all as shown in Fig. 5.

For changing the car to be suitable for the transportation of coal or gravel, or other material of a like nature, the bars 10 are replaced to their upright position, the entire sections I are swung under the roof, and are secured on their elevated position by turn-buckles 23, and the vertical sliding doors K are shifted up to 75 be under the roof, all as shown by Figs. 6 and 7; and for changing the car into a platform car the sub-sections a and b of sections I and the sub-sections c d of doors J are folded and turned under the trap-doors E E', and the 80 standards R are turned down into the notches T, all as shown in Fig. 8.

With the above devices it will be seen I produce a freight-car that contains all the parts necessary to be adaptable for carrying 85 any kind of freight, and that is strong and durable in its construction.

This car is also well adapted for a railway-inspection car, since either side or end can be opened for the officers to examine the condition 90 of the tracks.

I am aware that cars have been provided with side walls formed of sections, one of which is subdivided and the other provided with a window, and therefore I disclaim such. 95

What I claim is—

1. A freight-car provided with side walls formed each of two sections, each of which sections is subdivided and adapted to be folded within the car-body, as set forth. 100

2. The combination, in a freight-car, and with a sectional floor thereof, of sectional side walls adapted to be folded under sections of said floor, as set forth.

3. In a freight-car, the side walls composed 105 of sections I, arranged to be turned under the roof, and of sections H, to be turned under the floor, substantially in the manner and for the purpose set forth.

4. In a freight-car, the sections H or J, secured to the floor-beams by hinges 7, and composed each of two sub-sections, a and b or c and d, hinged together to be folded upon each other, and adapted to be turned into the spaces between the floor-beams of the car, and to be 110 concealed by trap-doors that form part of the floor of the car, all substantially as and for the purpose set forth.

5. In a freight-car, the sections H, secured to the floor-beams by hinges 7, and composed 115 each of two sub-sections, a and b, hinged together to fold upon each other, the section b being composed of bars 9 and 10, separately connected to bars 11 and 12, all substantially as and for the purpose set forth. 125

6. In a freight-car, vertical bars 11 and 12, for supporting horizontal bars 9 and 10, each pair pivotally secured to a single hinge, 7, forming part of a post-holding socket, 2, substantially as described and shown.

7. In a freight-car, the sections H, hinged at 130 7, in combination with latches 13 and 14,

secured to posts F, and adapted to lock such sections on their upright positions, all substantially as set forth.

8. In a freight-car, the sections I, hinged to roof-beams G in a manner to be turned from a vertical to a horizontal position, and to be temporarily secured by a holding device, 29, all substantially as and for the purpose set forth.

9. In a freight-car, the sections I, composed of horizontal bars 17, secured to vertical bars 19, and of horizontal bars 18, secured to vertical bars 20, such bars 19 and 20 being pivotally suspended to the roof-beams, all substantially as and for the purpose set forth.

10. In a freight-car, the sections I, composed of bars 17, secured to vertical bars 19, and of bars 18, secured to vertical bars 20, each pair of bars 19 and 20 being suspended on a common hinge, 21, that forms part of casting 22,

all substantially as and for the purpose set forth.

11. In a freight-car, the sections I, composed of bars 17, secured to hinge-bars 19, in combination with bars 18, secured to hinge-bars 20, and arranged to be suspended under the roof of the car by hooks 24, all substantially as and for the purpose set forth.

12. In a freight-car, the standards R, pivotally secured by bolts S, to be turned into notches T of floor-beams A and A³, all substantially as described, for the purpose specified.

In testimony whereof I affix my signature in presence of two witnesses.

MORRIS M. HIRSH.
